UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,850, dated October 24, 1893.

Application filed September 19, 1893. Serial No. 485,915. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of heraldic ornaments, placed equidistant, and small fluer-de-lis shaped ornaments disposed between them as represented in the accompanying drawing.

In the upper portion of the design, which forms the border, the heraldic ornaments are inclosed by foliated upright scrolls and above 15 the heraldic ornaments are crossed leaves or sprays.

What I claim is—

1. The design for wall paper herein shown and described. 20

2. In the design for wall paper the border herein shown and described.

Witness my hand this 15th day of September, 1893.

CHARLES BOOZE.
